US0D1015345S

(12) **United States Design Patent** (10) **Patent No.:** **US D1,015,345 S**
(45) **Date of Patent:** **** Feb. 20, 2024**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Heyungjoo Kim**, Suwon-si (KR); **Jisu Son**, Suwon-si (KR); **Miyeon Park**, Suwon-si (KR); **Jihyun Ahn**, Suwon-si (KR); **Minhwa Kim**, Suwon-si (KR); **Sera Park**, Suwon-si (KR)

(73) Assignee: **SAMSUNG ELECTRONICS CO., LTD.**, Gyeonggi-Do (KR)

(**) Term: **15 Years**

(21) Appl. No.: **29/823,073**

(22) Filed: **Jan. 13, 2022**

(30) **Foreign Application Priority Data**

Jul. 23, 2021 (KR) 30-2021-0035049

(57) **CLAIM**

The ornamental design for a display screen or portion thereof with graphical user interface, as shown and described.

DESCRIPTION

FIG. 1 is a front view of a first embodiment of a display screen or portion thereof with graphical user interface, showing our new design; and,

FIG. 2 is a front view of a second embodiment of a display screen or portion thereof with graphical user interface, showing our new design.

The outer perimeter broken lines in the figures depict a display screen or portion thereof and form no part of the claimed design. The remaining broken lines in the figures depict portions of the graphical user interface that form no part of the claimed design.

1 Claim, 2 Drawing Sheets
